UNITED STATES PATENT OFFICE.

JOHN F. O'CONNOR, OF CHICAGO, ILLINOIS, ASSIGNOR TO WILLIAM H. MINER, OF CHAZY, NEW YORK.

ADJUSTABLE SIDE BEARING FOR RAILWAY-CARS.

1,139,061.

Specification of Letters Patent.

Patented May 11, 1915.

Application filed July 25, 1914. Serial No. 852,998.

To all whom it may concern:

Be it known that I, JOHN F. O'CONNOR, a citizen of the United States, residing at Chicago, in the county of Cook and State 5 of Illinois, have invented a certain new and useful Improvement in Adjustable Side Bearings for Railway-Cars, of which the following is a full, clear, concise, and exact description, reference being had to the accompanying drawings, forming a part of this 10 specification.

This invention relates to improvements in adjustable side bearings for railway cars.

The object of the invention is to provide a 15 side bearing for railway cars in which one of the bearing members is made adjustable to compensate for wear and varying conditions of service.

In the drawing forming a part of this 20 specification, Figure 1 is an elevation of a body bolster and a truck bolster showing my improvements in connection therewith. Fig. 2 is an enlarged detail sectional view 25 of one of the side bearings taken substantially on the line 2—2 of Fig. 1. Fig. 3 is another detail sectional view taken on the line 3—3 of Fig. 2.

In the drawing, and referring to Figs. 1, 2 and 3, 10 denotes the body bolster and 11 30 the truck bolster of a railway car and which may be of any suitable construction. On each side of the king pin connecting the two bolsters, a side bearing is provided, as is customary, each of the side bearings, as 35 shown in the drawing, comprising a lower member A secured to the truck bolster and an upper member B secured to the body bolster. The bearing member A comprises a base casting 12 riveted or otherwise suit- 40 ably secured to the truck bolster, said base casting having pivotally mounted therein on trunnions 13, 13 a cradle 14 in which is rotatably mounted an antifriction roller 15.

The upper bearing member B which 45 comprises the wear or striking plate or thrust member, is shown as comprising a hollow box-like casting 16 having laterally extending flanges at the top thereof 17 by which it is secured to the body bolster by rivets 18 or other suitable means. The casting 16 has 50 end walls 19 and side walls 20, the end walls 19 each being provided with a horizontally extending elongated slot 21 surrounded by a rib 22. Extending through and support- 55 ed in the slots 21, 21 is a supporting rod or

bar 23, circular in cross section, as shown, and prevented from accidental displacement by cotter pins 24. Mounted on the rod 23 is an adjusting member 25, which, as shown, is in the form of a prism having a dodecagon cross section and provided with end walls 26. The end walls 26 are perforated as indicated at 27 to receive the rod 23 therethrough, the holes or perforations 27 being eccentrically disposed relatively to 60 the axis of the prism. Mounted on and carried by the adjustable prism member 25, is a carrying bracket 28 having an upstanding cylindrical like portion 29 provided on the inner side thereof with a plurality of faces 70 30 corresponding in size and angular relation to the 12 faces 31 on the prism 25. At its lower end, the bracket 28 has a horizontally extending base 32 to the under side of which is secured a wear plate 33 by rivets 75 34, the carrying bracket 28 having end strengthening flanges 35 as shown most clearly in Figs. 1 and 3.

With the parts as shown in Fig. 3, the wear plate is in its lowermost position but 80 to adjust the same relatively to the roller beneath and the body bolster by which it is carried, the rod 23 will first be removed whereupon the bracket 28 and the prism 25 may be removed. Thereupon, the prism is 85 withdrawn from one end of the bracket 28 and its angular position therewithin changed to the desired amount, thus bringing the perforations or holes 27 one side of the vertical line passing through the center 90 of the prism. After the foregoing adjustment has been made between the prism and the bracket, the parts are then inserted within the box-like casting 16 and the rod 23 inserted through the perforations 27 and the 95 rod is held within the casting by the cotter pins 24. With the construction shown and above described, it is possible to obtain six adjustments and yet the parts occupy a relatively small space.

Although I have herein shown and described in detail what I now consider the preferred method of carrying out my invention, yet I am aware that numerous changes and modifications may be made in the details 100 of construction and arrangements of the parts without departing from the spirit of the invention and all such changes and modifications are contemplated as come within the scope of the claims appended hereto.

105

110

I claim:

1. In a side bearing for railway cars, a striking plate, and means for adjusting the height of said striking plate, said means including an adjustable eccentric supporting member separable from the striking plate.
2. In a side bearing for railway cars, the combination with a casting adapted to be secured to a bolster, of a striking plate, and means for adjusting the striking plate relatively to said casting, said means including a supporting member separate from and adjustable to different angular positions relatively to said casting.
3. In a side bearing for railway cars, the combination with a bolster, of a casting secured thereto, a thrust member, and an eccentric support for said member adjustable angularly about a horizontal axis, the thrust member having a single bearing face.
4. In a side bearing for railway cars, the combination with a casting adapted to be secured to a bolster, said casting being provided with bearings, an eccentric supporting member mounted in said bearings, and a thrust member carried by said supporting member, the thrust member and eccentric supporting member being relatively adjustable.
5. In a side bearing for railway cars, the combination with a casting adapted to be secured to a bolster, of a thrust member, an adjustable support for said member, said support being a regular polygon in cross section.

JOHN F. O'CONNOR.
